UNITED STATES PATENT OFFICE.

JOSEPH E. CRISP, OF SOMERVILLE, ASSIGNOR TO JOHN STETSON, OF NEWTON, MASSACHUSETTS.

MACHINE FOR MEASURING INCOMPRESSIBLE FLUIDS.

SPECIFICATION forming part of Letters Patent No. 295,858, dated March 25, 1884.

Application filed October 13, 1883. (No model.)

To all whom it may concern:

Be it known that I, JOSEPH E. CRISP, of Somerville, in the county of Middlesex and State of Massachusetts, have invented certain new and useful Improvements in Machines for Measuring Incompressible Fluids under Pressure, and in motors moved by such fluids, of which the following is a full, clear, and exact description, reference being had to the accompanying drawings, forming a part of this specification in explaining its nature, in which—

Figure 1 is a vertical cross-section through one of the cylinders, showing the pistons connected to the cam, the cam, the inlet and the outlet casing, and the air-chamber. Fig. 2 is the base of the machine, partly in plan and partly in section, showing the cylinders, settling-chambers, pistons and piston-valves, and the connections between the pistons and cam. Fig. 3 is a plan of the cam. Fig. 4 is one of the pistons and piston-valves in perspective. Fig. 5 is one of the piston-connections in perspective.

The object of this invention is to produce a machine that can be manufactured at a minimum cost, of maximum durability, not affecting materially the head or pressure of the liquid, measuring correctly when a small quantity of fluid is flowing from the outlets, and not retarding the flow when a large supply is required. It relates to improvements upon the subject-matter of my Patent No. 142,559, dated September 9, 1883; and these improvements consist, first, in forming the inclines of the cam so as to make the separate or combined movements of the pistons the same for each degree of revolution made by the cam or cylinders to cause the stream of fluid flowing from the machine to be without pulsation in the pipes used for distribution; second, in making the pistons single-acting, so that rolls connected with them will at all times bear out against the working-face of the cam, preventing noise or click, and also keeping the stroke of the pistons or capacity of the machine unchanged if the rolls should wear; third, in forming the inclines of the cam so that the valves have any required lap inside or outside; fourth, in using the cam to move the register; fifth, in chambers in connection with the measuring-cylinders for preventing injury

to working parts of the machine; sixth, in pistons and piston-valves of the same diameter, combined with the parts to reduce retardation of the current; seventh, in an air-chamber to assist the movements of the machine when there is but little flow from the outlets, and to prevent the fluid covering the face of the register.

The following will explain the construction and operation of my improved machine to those skilled in the art.

The cylinders, (Figs. 1 and 2).—The base A is circular in form, and cast integral with it are the cylinders A' at right angles to each other, with the settling or measuring chambers A³ in the angles between the cylinders. The cylinders A' are connected in the center to the inlet A², and with the chambers A³ by the ports A⁴ and A⁶, as shown. The ports A⁴ and A⁶ are cast square, and the port A⁴ leads from the outer end of the cylinders to the chambers A³, A⁶ to the chambers A³ from near the center, and A⁷ up to the outlet-casing. The ends of the cylinders have the heads A⁹. The chambers A³ receive and deliver the fluid to be measured. After these chambers and the cylinders are filled, but little, if any, change of fluid in the measuring-cylinders will take place, and injurious substances have small chance of contact with those cylinders and the pistons moving therein. Neither do the cylinders require vent to remove air upon starting the machine. The pipe leading from the main opens into the inlet A². A⁵ is the spindle for the cam C to revolve around.

The pistons and piston-valves, (Figs. 1, 2, and 4).—The pistons are single-acting, pressure upon the valve end forcing them outward, the inclines of the cam drawing them toward the center, and the measuring-pistons B move in the outer ends of the cylinders A', moving fluid in the chambers A³ through ports A⁴. Connected with the measuring-pistons B, by an intermediate ring, B² of smaller diameter, are the piston-valves B', that moving past the ports A⁶ at proper times, connect them with the inlet A² for pressure, or A⁷ to exhaust. These valves being the same diameter as the pistons, and the ports being, substantially, 100 grooves around the cylinders, they are perfectly balanced; and since each port-opening

is one-third or more of the stroke, the combined area of port openings at all times is largely in excess of the inlet and outlet, so there will be little or no retardation of the fluid 5 passing through the machine by friction in the passages.

The pistons and valves are connected to the cam C in this manner: Loosely fitting between the piston B and the valve B' is a downward 10 projection, D, of the swinging arm b, which moves over the exhaust-port A⁷, Fig. 1, this arm D being pivoted to the base A at A⁸, and is on top provided with a pin, D², to carry the roll E, which in turn bears against the cam C, 15 the whole connection being firm, yet moving freely. The outlet-casing F, Fig. 2, is firmly bolted to the base A, inclosing the register, the cam C, and the exhaust-ports A⁷, its top being a strong glass-plate, F', made tight by a 20 gasket above, and held up by the ring F², the pressure inside assisting to form the joint. The outlet F³ being below the top of the casing, and the casing perfectly air-tight, sufficient 25 of the air carried by the fluid passing through the holes in the web of the cam will be retained to prevent the fluid under pressure from flowing over the top of the register. In fact, the register is placed in an air-chamber with a glass top, through which its measurements 30 can be observed, this air-chamber almost touching the web of cam C. The use of this air-chamber assists materially the operation of the machine, as the air in the air-chamber is compressed by the pressure of the fluid within the machine, and if that pressure 35 varies, as it does vary constantly, the expansion of air acting upon the fluid in the machine when the pressure in the main is reduced throws or moves the piston, and therefore the cam, in a reversed direction, the extent of which will vary according to the extent of the reduction of the pressure; and upon the return of the pressure the cam is moved forward a somewhat greater distance on account 40 of the reduction of pressure upon the outlet side of the machine than it would if the pressure or throw had remained constant. The cam C, Figs. 2 and 3, revolves around the bearing A⁵, and is driven by the outward motion 45 of the pistons pressing the rolls E at the proper times against its inclines, the reverse inclines drawing the pistons back to the starting-point. The rolls E are always in contact with the outer side of the cam-path, the inner side of the cam-path keeping the pistons in 50 their relative position when there is no pressure upon them. The rotation of the cam also actuates the register, which is adapted to be placed in the air-chamber above it. The cam 55 can be so arranged that the pistons and valves make any desired number of strokes to a revolution, and it is so designed that when one pair of pistons and valves is at rest the other pair of pistons and valves is moving at such a speed as will cause the flow of fluid, and of course the power driving the cam around, to be constant; and it is accomplished, substan-

tially, in this way: On the drawing, Fig. 3, it will be seen that the cam shown will, by one revolution, cause each piston to have five outward and five inward strokes, each end of the cylinders receiving and delivering fluid five times. Thus a revolution of thirty-six degrees fills one end and empties the other of each cylinder. This thirty-six degrees is divided into twelve equal parts, and the motion forward of one piston and valve, and backward of the other piston and valve, of either cylinder is represented by thirty of these parts, and the period of rest by six of these parts, divided substantially as follows: 0 0 1 2 3 4 5 5 4 3 2 1, two spaces allowing the pistons to rest, while the valves carried by the other pair of pistons are disclosing the ports for pressure and exhaust. The cylinders being at 85 right angles to each other, the sum of their combined strokes for each space included within the thirty-six degrees, or one stroke, is for one cylinder 0 0 1 2 3 4 5 5 4 3 2 1; for the other cylinder, in the same times, 5 5 4 3 2 1 0 0 1 2 3 4; 90 and for the cylinders combined, 5 5 5 5 5 5 5 5 5 5 5 5. This is equally true for each of the strokes represented by the cam. The cam C may have any other number of inclines than five—say one, three, seven, &c., as desired— 95 and if laid out as described above the result will be the same. If designed for a motor using elastic fluid acting expansively, it can be laid out so that the speed of pistons combined for each degree of revolution at any elected grade 100 of expansion shall give the same result—namely, equal power to revolve the cam at all points.

An inspection of the figures above show, that when either pair of pistons and valves is 105 at rest the other pair moves ten parts, or one-third of their stroke; and the valves can be made, if desired, one-third of the stroke longer than the ports they move over, and yet disclosing them (the ports) at the proper time. 110 Furthermore, it would require excessive damage of the valve and port corners before the fluid could flow past both sides of the valves at the same time and balance the pistons. Using a cam perfectly blending the strokes of 115 the pistons prevents undulations in the stream flowing from the machine, and jar or hammer in the pipes used for distribution will not occur; and since the rolls which control the motions of the pistons and valves at all times bear out against the cam, the valves can be so arranged that within certain limits the effect of wear is automatically provided for, and the measuring capacity will remain unchanged. 120 Near the center of the cam are small holes 125 through the web to allow air (that separates from the dense fluid passing through the machine) to reach that part of the outside casing containing the register, the web of the cam preventing the current from disturbing 130 the contents of the air-chamber. If used as a motor, a wheel can be attached to the cam, or the cam held firm and the base revolved.

Operation of the machine.—If properly con-

nected, with the outlets closed, admission of inelastic fluid under pressure will fill the inlet-chambers, cylinders, and outlet-casing, compressing the air in the air-chamber to a volume due to the pressure. On opening any of the outlets the movements of any one of the pistons and piston-valves can be described thus: When a valve moving outward discloses a port, A⁶, to the inlet A², the fluid is in communication with a chamber, A³, to its left, and balances the piston and valve in the end of the cylinder connected to that chamber by the port A⁴, and an incline of cam C can draw that piston and valve toward the center, the fluid following the measuring-piston will draw into the chamber A³ through A⁶ as the piston moves toward the center after the piston and valve have reached their innermost point of travel and had the proper time of rest. The same valve, now moving inward, discloses the port A⁴ to the exhaust-port A¹, and allows pressure against the inner end of the piston-valve to force it outward, the piston moving the fluid before it, and a quantity equal to that displaced will pass up exhaust-port A⁷ into the outlet-casing F, and in due time from the machine. During the outward motion of the piston and valve, a roll, E, is forced out against an incline of cam C, causing it to revolve and making a reverse incline, acting against another roll, E, draw in the piston, and valve off, and fill the other end of the cylinder.

Reference to the description of the cam C will give the combined operation of all the pistons and valves when the motion of the machine is constant.

It will be observed that the arm D' of the device connecting each set of pistons with the cam is held between the shoulders d d' of the said pistons B B', and that as the said arm D' is moved upon an arc of a circle by the cam, it follows that when the end bears against the shoulder d in moving the piston, moving as it does upon the arc of a circle, it partially revolves the piston on each of its inward strokes, so that the piston is entirely revolved by a comparatively few strokes. The arm D' in this respect acts something like a pawl, and the shoulder d like a ratchet—that is, the end of the arm when the piston is way out takes hold of the flange or shoulder, and upon the inward movement of the piston, on account of the changed position consequent upon the movement given it, it throws the piston in the direction of its movement, and upon the outward movement, as the cam does not then move the piston, the arm does not contact with the shoulder d' with sufficient stress to move the piston. This revolution of the piston in the cylinder is of very great advantage, because it makes the wear of the pistons uniform and to a very great extent prevents scoring, and the wear of the connection D' on the shoulder d is distributed throughout the entire extent of the shoulder.

It will be noticed, therefore, that my ma-

chine consists, essentially, of a number of pistons, which are successively operated by the pressure of fluid to open certain valves upon their outward movements, and which are returned to their original position, or in a position to be again moved outward by cam-inclines upon a cam-disk, and that the movement of a piston in an outward direction causes a revolution of the cam-disk and a cam-incline to move inward an oppositely arranged piston; that there is arranged a system of ports and passages which permit the escape of fluid from the central chamber through intervening settling-chambers to the measuring-chambers, from which or from the settling-chambers the fluid passes into the chamber in the upper section of the meter, and thence through the outlet.

It will also be observed that the connections between the pistons and the revolving cam-disk are pivoted to the casing of the meter, so as to be swung or moved by the action of the pistons and by the cam grooves or inclines. These swinging arms or connections have two projections, one of which fits the space in each piston, between the inner and outer portions thereof, and the other of which enters the cam-groove in the cam-disk; and upon the outward movement of the pistons these connections are swung outwardly, thereby causing the cam-pins to revolve the cam-disk, and by so doing the cam-disk is caused to move inwardly by means of the same connections, the pistons, which are balanced by the water-pressure, being uniform on each side, which is the case when the measuring and settling chambers are filling with water and ports are open to allow the entrance or passage of fluid from the inlet; and it will further be seen that the arrangement of pistons and ports and the cam-inclines is such that when a piston is being forced outward by pressure to expel the fluid from the measuring-chamber its oppositely arranged piston is being drawn inward by the revolution of the cam, and these movements of pistons out and in are successive and continuous so long as the fluid is allowed to escape from the meter.

I do not broadly claim the use of pistons for measuring liquid, arranged oppositely to each other, and in which the movement of one piston causes the movement of another; but I am not aware that any device for measuring incompressible fluids has been invented which contains pistons connected with each other by a cam-disk, which they revolve, and which contains the essential elements of my device, as herein described.

Having thus fully described my invention, I claim and desire to secure by Letters Patent of the United States—

1. In a machine for measuring inelastic fluids under pressure, the combination of the pistons B B', the cam-disk C, the air-chamber F², the inlet A², and the outlet F³, all substantially as described.

2. In a machine for measuring inelastic

fluids under pressure, the combination of the inlet A², the cylinders A', the chambers A³, connected with the outer ends of the cylinders by the ports A⁴, the chambers A⁵, connected with the inlet A² by means of the ports A⁶, the ports A⁷, connecting with the chambers leading to the outlet-passage F⁸, the piston-valve B B', the cam-disk C, and the pivoted connections D D', connecting the pistons with the cam-disk, all substantially as and for the purposes described.

3. In a machine using elastic or inelastic fluid, the combination of a cam, laid out and operating substantially as described, with the pistons moving in two cylinders at right angles to each other.

4. In a machine using elastic or inelastic fluid, a cam, as described, which allows the pistons periods of rest and maximum motion, substantially as and for the purpose set forth.

5. In combination with the pistons B B', cam C, and the swinging arms D, each of which is pivoted to the casing of the meter, and has the cam-pin D², which engages with the cam C, and an arm, D', which engages with the piston, all substantially as and for the purposes described.

6. In a machine using elastic or inelastic fluid, the combination of a cam with single-acting pistons and piston-valves, whereby the pistons are caused to act in unison in opposite ends of the cylinders, and an automatic adjustment for wear thereof provided, all substantially as and for the purposes described.

7. The combination, in a meter or motor, of two or more cylinders, their ports A⁴ A⁶ A⁷, chambers A³, separate pistons B, piston-valve B', and the cam for returning the piston successively to a position to be again operated upon by the pressure, all substantially as and for the purposes described.

8. The combination, in a meter or motor, of a central chamber or pressure-supplied passage, two or more cylinders radiating therefrom, their pistons adapted by the pressure in the said central chamber or supply-passage to be moved successively outwardly in their respective cylinders, supply and exhaust ports and their valves, the outlet-passage F⁸, and a cam for returning the pistons to a position to again take the pressure, all substantially as described.

9. In a motor or meter, the piston B, operated by the pressure of the fluid in one direction and by a cam in the reverse direction, and the intermediate pivoted connections D D', connecting the piston with the cam, and shaped as described, whereby the piston is partially revolved during each complete reciprocation, all substantially as and for the purposes set forth.
